UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

BOX-FILLING MACHINE.

1,386,243.

Specification of Letters Patent.

Patented Aug. 2, 1921.

Original application filed May 7, 1918, Serial No. 233,081. Patent No. 1,326,187. Divided and this application filed June 5, 1919. Serial No. 301,981.

To all whom it may concern:

Be it known that I, JOSEPH C. DONNELLY, a citizen of the United States, and resident of Barberton, in the county of Summit and State of Ohio, have invented certain new and useful Improvements in Box-Filling Machines, of which the following is a specification.

The subject of the present application, which is a division of my application for Patent No. 1,326,187, dated December 30th, 1919, concerns certain improvements in and relating to machines for filling the tray-and-shuck form of box commonly employed for holding matches.

The present invention comprises mechanism whereby complementary trays and shucks are delivered in an orderly manner from separate sources of supply and are properly positioned in endwise relation to each other preparatory to the operation of filling the trays and entering them within their associated shucks, which mechanism, in the preferred form of embodiment of my invention, will be hereinafter described in detail, and the scope of the invention then be defined in the appended claims.

In the drawings—

Figure 1 is a plan of a portion of the tray and shuck receiving end of a box-filling machine embodying my invention.

Fig. 2 is a side elevation of the same, partly in section.

Fig. 3 is a longitudinal vertical section through the lower portion of the tray-feeding chute and adjuncts; the tray transfer wheel being in elevation, and the receiving end of the box carrier being in section.

Fig. 4 is a partial side elevation of the lower portion of the tray-feeding chute and adjuncts, including the transfer wheel, the tray-releasing device controlled thereby, and the receiving end of the box carrier.

Fig. 5 is a partial transverse vertical section through the box carrier and adjuncts, looking toward the tray and shuck feeding devices, the guard for the tray transfer wheel being broken away, and the shuck feeding hopper being omitted for clearness.

Fig. 6 is a transverse section through the tray chute and adjuncts, as on the line 6—6

of Fig. 4; showing the relative positions of the adjacent portions of the temporary match holders and the box carrier.

Fig. 7 is an elevation of the delivery end 55 of the tray-feeding chute, and its adjuncts, including the tray transfer wheel; a tray, partly in section, being shown as engaged by the wheel.

Fig. 8 is a sectional elevation of the frictional drive gear, and adjuncts, for the tray transfer wheel.

Fig. 9 is a perspective view of spaced tray-supporting fingers at the delivery end 65 of the tray chute, together with a spring stop device for a tray; such tray being shown as positioned on the fingers.

Referring to the drawings, 29 designates a portion of an endless chain of temporary match holders arranged to travel adjacent 70 the match carrier of a match machine and to receive and assemble the matches discharged therefrom. This chain is guided about a pair of suitably-disposed sprocket wheels at the respective ends of the machine, the shafts of which wheels are supported in a horizontal table or bed 32. The sprocket wheel, 31, and its shaft, 34, at the tray and shuck receiving end of the machine are shown. This shaft is stationary 80 and its wheel is mounted to turn freely thereon; but the shaft having fast thereon the sprocket wheel (not shown) at the opposite end of the machine is geared with and driven from a shaft 37 to which motion is 85 transmitted from a suitable source of power.

39 designates a portion of a box-carrier comprising an endless chain of links provided with box receptacles which correspond in number and relation with the temporary 90 match-holders and are arranged to travel adjacent to and at the same speed as said holders; each of which receptacles is constructed and arranged to hold a tray and its complementary shuck in endwise relation to each other.

45 designates a sprocket wheel about which the box-carrier passes at the tray and shuck receiving end of the machine. The shaft 46 of the wheel 45 is provided with a 100 gear wheel 47 in mesh with a similar wheel 48 fast on a short, longitudinally-disposed

shaft 49 having its bearings in brackets on the underside of the bed. The shaft 49 bears a gear wheel 50 in mesh with a similar wheel 51 on the shaft 37 which actuates the match 5 holders.

The parts above mentioned being of known construction and operation need not be herein more particularly described.

The mechanism for supplying trays and 10 shucks in an orderly manner to the box carrier, comprises two magazines 82, 83 for trays and shucks respectively.

The tray magazine 82 includes in its construction a vertical chute having at its lower 15 end a curved portion 84 which leads toward and terminates immediately in advance of the tray bearing portion of the box carrier as the latter approaches its upper horizontal path at the receiving end of the machine. 20 The chute is supported by a suitable bracket 85 on the main frame. The trays are delivered side by side to the upper end of the chute, and fed down the same, such trays being gradually turned to a position with their 25 bottoms downward as they pass along the curved lower portion of the chute and being thus advanced consecutively to and beyond the delivery end of the chute preparatory to their transference to the succeeding 30 holders of the box carrier. Projecting horizontally from the floor of the chute at its delivery end are two spaced fingers 86 upon which the succeeding leading trays are temporarily supported as they leave the chute. 35 Between the fingers, adjacent their outer ends, is a yielding up-standing stop against which the outer end of the leading tray contacts, which stop, in the present instance comprises an up-standing teat 87 formed 40 on the free end of a spring which is affixed to a suitably-disposed lug on the bracket 85. (See Figs. 3, 4, 7 and 9.)

A feed wheel 88 overhangs the receiving 45 end of the box carrier and acts upon the succeeding trays on the supporting fingers 86 so as to transfer such trays consecutively to the tray-supporting portions of said carrier. This wheel is fast on one end of a horizontal shaft 89 having its bearings in 50 brackets 90 rising from the bed 32. (See Figs. 1 and 5.) On the opposite end of the shaft 89 is mounted a pinion 90 in mesh with a spur wheel 91 on the shaft 46 which carries the driving sprocket wheel 45 for the 55 box carrier. The pinion is frictionally held on the shaft 89 by means, for example, of lateral friction washers 78 which embrace the wheel and are held in contact with the respective sides of the latter by means of 60 collars 79, the outer one of which is adjustable by means of a nut 80 on the screw-threaded end of the shaft.

The ratio of the gears 90, 91 is such that 65 the feed wheel is driven at much higher speed than the box carrier, except when the

movement of the feed wheel is temporarily retarded, as hereinafter described, in which case the frictional connection permits relative variable movement between the pinion and feed wheel.

70

The wheel is provided with a series of peripheral projections 92 which are regularly spaced apart and are so disposed in relation to the trays as to impinge successively against the inner walls of the consecutive trays on the supporting fingers 86 at the delivery end of the chute with sufficient force to depress the spring 87. The wheel is provided, adjacent the respective projections, with inserts 94, preferably of hard metal, which are arranged to contact successively with the opposing walls 43 of the box holder. As each insert contacts with a wall 43 the movement of the rapidly rotating wheel is temporarily retarded to accord with that of the box carrier, but when the box holder advances sufficiently to permit the escape of the insert the wheel is rapidly advanced until the next succeeding insert contacts with the following wall of the holder. During the quick movement of the wheel the tray is rapidly moved to position for delivery to the box carrier. The acting portion of each of the projections is rounded and made smooth, as at 93, so that when a tray is pushed above the carrier by such portion, the tray may freely fall between the walls 43 of the underlying box holder. The inserts 94 obviate any liability of the portions 93 contacting with the walls 43 and thus becoming rough or abraded.

In order to prevent the endwise displacement of each succeeding tray at the delivery end of the chute, preparatory to its engagement by a wheel projection 93, I provide a 105 light latch lever which is pivoted to a bracket 95 on a forward lateral extension of the lower end of the chute. The longer arm 96 of the lever is provided with a depending lip 97 which normally lies within the 110 leading box in close relation to the inner wall of the latter. The other arm 98 of the lever extends into the path of a series of tappet studs 99 on one side of the wheel, which studs correspond in number and 115 spaced relation with the projections 92, whereby during the rotation of the wheel the studs successively impinge against the arm and thus actuate the lever to effect and permit the alternate raising and lowering of 120 the lip from and into the underlying tray respectively. When the lip is engaged with the inner wall of the leading tray, such lip co-acts with the yielding stop 87 to hold the tray in place. When the lip is raised a 125 wheel projection enters the tray and advances it as previously explained.

The shuck magazine 83 (Figs. 1 and 2) includes in its construction a vertical chute having at its lower end a curved portion 130

100 which leads toward and terminates immediately above the shuck bearing portion of the box carrier as the latter approaches its upper horizontal path at the receiving 5 end of the machine. The chute is supported at its lower end between a pair of spaced webs 101 formed on a bracket 102 which is affixed to the bed. Successive shucks, with their narrow sides in contact with each 10 other, are delivered to the upper end of the chute 83 and fed down the same, such shucks, similarly to the trays, being gradually turned to a horizontal position as they pass along the curved lower portion of the chute 15 and being thus advanced consecutively to the delivery end of the chute where they fall, by gravity, into their respective holders on the box carrier.

The top of the lower curved portion of 20 the chute 83 is preferably constituted by a sector 103 which is pivoted between the webs 101, as indicated at 104 Fig. 2, so that said sector can be readily swung upward in order to secure access to the lower part of 25 the chute, or the shucks therein, as occasion may require.

In order that the feeding of the shucks and trays to the box carrier can be simultaneously discontinued at will without the 30 otherwise necessity of stopping the operation of the main machine, mechanism of the following character is provided, reference being had to Figs. 1 to 5, inclusive, of the drawings:

35 105 designates a dog comprising a strip of spring metal affixed at its upper end to a vertical chute cover plate 106 supported on the bracket 85. The lower end of the strip has an inturned lip 107 which extends 40 through an opening 108 in the adjacent wall of the chute and, by actuation of the strip, is movable into and from the vertical path of the trays in the chute. The inherent elasticity of the strip maintains the latter normally retracted from the trays, as seen in 45 Fig. 3. The body of the strip is bent outward as at 109, into the active path of a cam 110, which is formed on the upper end of an arm 111 rising from a longitudinally 50 slidable shifter rod 112 extending transversely of the machine. By actuating this rod the cam 110 can be moved against the strip so as to force the latter toward the chute and move the lip 107 into the path 55 of the trays within the chute, and thus check their descent.

A horizontally disposed plunger 113 (Figs. 1 and 2) is movable into and from one side of the shuck chute, through an orifice in the latter, so as to contact with or release the shuck opposed thereto within the chute. This plunger is guided within a casing 114 fast on the perforated wall of the chute, and is normally held in retracted 60 position by means of a confined spring 115

which, encircling the plunger, bears against a collar 116 on the latter and against the opposing wall of the chute. The outer end of the plunger extends into the active path of a cam block 117 fast on the rod 112. 70 This cam is so shaped and positioned relatively to the cam 110, that when the rod is shifted, as above mentioned, the cam 117 bears against the end of the plunger at the same time the cam 110 contacts with the 75 strip 105, thus checking the progress of the shucks simultaneously with the stopping of the tray feed. When the rod is retracted to its original position the cams are withdrawn from engagement with the dog and 80 plunger, respectively, thus permitting the retraction of the dog and plunger and consequent release of the trays and shucks in their respective chutes.

In the present instance a spring 118 attached to the rod and to a fixed part of the machine holds the rod normally in a position with the cams 110, 117 retracted from the dog and plunger respectively; one corner of the cam 117 being notched, as at 119, 85 so as to bear against the proximate corner of the chute 82 and thus limit the retracted position of the rod. (See Figs. 1 and 2).

120 (Figs. 1 and 2) designates a portion of an endless chain which leads to and effects the operation of certain mechanisms for supplying the trays and shucks in an orderly manner to the upper or receiving ends of their respective chutes; but as such mechanisms form no part of the present invention it is unnecessary to show or describe them herein. Suffice it to say that the operation of the chain is controlled simultaneously with that of the devices above described for checking and releasing the trays 105 and shucks within the respective chutes; such chain control being effected by operatively connecting one end of the shifter rod 112 with an upstanding lever 121 which is constructed and arranged to determine by 110 its actuation the active and idle positions of a clutch 122 for a chain driving wheel 123. This wheel and its clutch are mounted on a shaft 124 bearing a pinion 125 in mesh with the gear wheel 91 on the shaft 46 previously 115 described.

It is to be understood that my invention is not limited to the specific construction herein disclosed, as the same may be modified within the principle of my invention and 120 the scope of the appended claims.

I claim—

1. The combination with a carrier having a succession of tray holders comprising spaced transverse walls, and means for impelling the carrier, of a tray-feeding element terminating in a tray receiving and supporting member adjacent the path of the walls of said holders, a yielding stop with which the leading trays successively contact when 125 130

they are delivered to said member, a rotary feed wheel overhanging the carrier and having spaced projections which contact with the inner walls of the successive trays 5 on the said member and also with the succeeding walls of the tray holders, and impositive driving means for actuating said wheel at a normally higher speed than the carrier.

10 2. The combination with a carrier having a succession of tray holders comprising spaced transverse walls, and means for impelling the carrier, of a tray-feeding element terminating in a tray receiving and 15 supporting member adjacent the path of the walls of said holders, a yielding stop with which the leading trays successively contact when they are delivered to said member, a lever having a stop portion which enters 20 said trays in succession, a rotary feed wheel overhanging the carrier and having spaced projections which contact with the inner walls of the successive trays on the said member and also with the succeeding walls 25 of the tray holders, tappet studs on the wheel co-acting with the said lever, and impositive driving means for actuating said wheel at a normally higher speed than the carrier.

30 3. The combination with a carrier having a succession of tray holders comprising spaced transverse walls, and means for impelling the carrier, of a tray-feeding element terminating in a tray receiving and 35 supporting member adjacent the path of the walls of said holders, a yielding stop with which the leading trays successively contact when they are imposed on said member, a rotary feed wheel overhanging the carrier and having spaced projections which contact with the inner walls of the successive trays on the said member, said projections including protective inserts which contact with the succeeding walls of the carrier, and 40 impositive means for actuating said wheel at a normally higher speed than the carrier.

4. The combination with a carrier having a succession of receptacles for trays, of a tray chute having a curved delivery portion 50 leading toward the receiving portion of the carrier and terminating in spaced tray receiving and supporting fingers in proximity to the path of the carrier, a downwardly yielding stop with which the forward lower 55 edges of the leading trays successively contact when they are delivered to said fingers, a rotary feed wheel overhanging the carrier and the fingers and having spaced projections which contact with the inner walls of 60 the successive trays on the said fingers and transfer said trays to the adjacent receptacles of the carrier, and means for actuating said wheel.

5. The combination with a carrier having 65 a succession of receptacles for trays, of a

tray chute having a curved delivery portion leading toward the receiving portion of the carrier and terminating in spaced tray receiving and supporting fingers in proximity to the path of the carrier, a yielding stop 70 with which the trays successively contact when they are imposed on said fingers, a lever having a stop portion which enters said trays in succession, a rotary feed wheel overhanging the carrier and having spaced projections which contact with the inner walls of the successive trays on the said fingers and transfer said trays to the adjacent receptacles of the carrier, tappet studs on the wheel co-acting with the said lever, and 75 means for actuating said wheel.

6. The combination with a carrier having a succession of tray holders, and means for impelling said carrier, of a tray-chute having a curved delivery portion leading to the 80 receiving portion of the carrier and terminating in spaced tray receiving and supporting fingers in proximity to the path of the carrier, a yielding stop with which the leading trays successively contact when they are imposed on said fingers, a rotary feed wheel overhanging the carrier and having spaced projections which contact with the inner walls of the successive trays on the said fingers and transfer said trays to the 85 adjacent tray holders of the carrier, said projections including protective inserts which contact with the walls of the succeeding tray holders, and impositive driving means for actuating said wheel at a normally higher speed than the carrier.

7. The combination with a traveling carrier, of a chute for feeding trays successively thereto, and a chute for feeding shucks to said carrier, of a stop member movable into the body of the tray chute, a stop member movable into the body of the shuck chute, and manually operable means for concertedly operating said stop members independently of the carrier, whereby the feeding of 105 the trays and shucks in the respective chutes can be simultaneously discontinued independently of the operation of the carrier.

8. The combination with a carrier having a succession of tray holders comprising 110 spaced transverse walls, and means for impelling the carrier, of means for feeding trays successively adjacent the receiving end of the carrier, a rotary feed-wheel overhanging the receiving end of the carrier and having spaced projections which contact with the inner walls of the succeeding leading trays and also with the succeeding walls of the tray holders, and impositive driving means for actuating said wheel at a normally 115 higher speed than the carrier.

9. The combination with a carrier having a succession of tray holders comprising spaced transverse walls, and means for impelling the carrier, of a tray-chute having a 120

curved delivery portion leading toward the receiving end of the carrier, a rotary feed-wheel overhanging the receiving end of the carrier and having spaced projections which contact with the inner walls of the succeeding leading trays and also with the succeeding walls of the tray holders, and impositive

means for actuating said wheel at a normally higher speed than the carrier.

Signed at Barberton, in the county of 10
Summit and State of Ohio, this 2nd day of
June, A. D. 1919.

JOSEPH C. DONNELLY.
